Primary Examiner — Michelle E. Wilson(74) *Attorney, Agent, or Firm* — Law Offices of Albert Wai-Kit Chan, PLLC(57) **CLAIM**

I claim the ornamental design for a Tai Chi sword brush, substantially as shown and described.

DESCRIPTION

FIG. 1 is a lateral view of the Tai Chi sword brush showing an elongated sword-shaped body (1) comprising a hand grip blade (2), a feather-tail string (3) and a pointed cylindrical artist's brush (4).

FIG. 2 is a top view of the Tai Chi sword brush showing the feather-tail string (3) and hand grip blade (2); and,
FIG. 3 is a bottom view of the Tai Chi sword brush showing the pointed cylindrical artist's brush (4) and hand grip blade (2).**1 Claim, 3 Drawing Sheets****FIGURE 1**
